UNITED STATES PATENT OFFICE.

JAMES E. FERGUSON, OF DWIGHT, ILLINOIS.

LUBRICANT-DISPENSER.

1,162,997.

Specification of Letters Patent.

Patented Dec. 7, 1915.

Application filed March 5, 1915. Serial No. 12,456.

To all whom it may concern:

Be it known that I, JAMES E. FERGUSON, a citizen of the United States, residing at Dwight, in the county of Livingston and State of Illinois, have invented a new and useful Lubricant-Dispenser, of which the following is a specification.

The present invention relates to improvements in a lubricant dispenser, one object of 10 the invention being the provision of a novel and improved dispensing machine adapted to be used in garages or elsewhere for use in dispensing heavy oils, such as grease, and other liquid or semi-liquid substances. 15 Another object of the invention being the provision of a novel mechanism, wherein a main supply has means simultaneously operated to deliver into a dispensing chamber, a predetermined quantity of lubricant, said 20 dispensing chamber being further provided with means for projecting the lubricant thereupon as dispensed and for simultaneously cutting off communication between the chamber and the main supply 25 tank.

A further object of the present invention, is the provision of a device of this character which may be easily operated without soiling the clothes and hands of the operator 30 and which by the simple manipulation of a crank connected to a single shaft will operate mechanisms for removing a predetermined amount of lubricant from the main supply tank to a dispensing chamber and 35 for removing the same lubricant from such chamber as desired.

With the foregoing and other objects in view which will appear as the description proceeds, the invention resides in the combination and arrangement of parts and in the details of construction hereinafter described and claimed, it being understood that changes in the precise embodiment of the invention herein disclosed can be made 45 within the scope of what is claimed without departing from the spirit of the invention.

In the drawings, Figure 1 is a view partly in elevation and partly in section of the complete mechanism, the respective pistons of the main tank and the dispensing chamber being in intermediate position. Fig. 2 is a top plan view of the complete mechanism. Fig. 3 is an enlarged detail sectional view of the lower portion of the supply tank showing the dispensing chamber. Fig. 4 is a top plan view of the dispensing chamber show-

ing a portion of the tank in section and the feed screw for the plunger of the dispensing chamber in section. Fig. 5 is a section taken on line 5-5 of Fig. 3. Fig. 6 is 60 a section taken on line 6-6 of Fig. 3.

Referring to the drawings, the numeral 1 designates the cylindrical walls of a main dispensing or supplying chamber or tank, which is provided with the removable disk 65 bottom 2, with the center bearing opening 3 for the feed screw 4, said feed screw 4 is of substantially the same length as the cylindrical portion of the tank and is provided at its upper end with the squared portion 7, 70 while mounted intermediate upon the screw for movement up and down as the screw is rotated, is the disk plunger 5, which is provided with radiating arms 6, which constitute a means for engaging the lubricant with- 75 in the tank to hold the disk against rotating during the longitudinal movement thereof upon the screw. It is also apparent that the disk 5 may be held against rotation by other means as for instance as a spline connected 80 to the periphery thereof in the interior of the tank 1, but it has been found in practice that the radial arms 6 are all that is necessary inasmuch as the lubricant is usually a stiff "grease" and therefore offers sufficient resistance to maintain the disk 5 85 against rotation.

The upper end 7 of the feed screw 4 is adapted to fit within the squared socket 8 of the short or stub shaft 9, which is rotatably mounted in the removable cover or disk 10 of the tank 1. This cover 10 is adapted to be held in place by means of the arm 11 which is connected to the upper surface of the cover and the hook 12. This 90 renders it necessary to slightly oscillate the cover 10 so as to disengage the arm 11 from the hook 12 when it is desired to remove the cover 10 and fill the tank as will later appear. A large bevel gear 13 is carried by 100 the shaft 9 and consequently by the cover 10, while also carried by the cover 10 to one side thereof is the bracket 14, which is provided with the pivoted member 15 which is normally held in encircling relation by 105 means of the thumb screw 16, so that the short section 17 of the shaft may be properly journaled therein with the parts in the position as shown in Figs. 1 and 2, or whereby the member 15 may be thrown backwardly to permit the shaft 17 to be elevated upon its hinge joint 19 so as to place 110

the gear 18 out of mesh with the gear 13 and thus permit the removal of the cover 10 to have access to the tank 1.

The other section 20 of the drive shaft is journaled upon the bracket 14' so that the brackets 14 and 14' constitute a support for the shaft consisting of the sections 17 and 20. Clutch members 21 and 22 are carried by the shaft sections and the spring 23 normally holds the clutch members together, so that when the crank 24 is rotated counter clockwise, the gear 18 is rotated and consequently the feed screw 4, the same being moved to the left so that the plunger 6 is moved downwardly and the plunger 36, as will presently appear is moved upwardly. When the crank 24 is moved in the opposite direction, the clutch members 21 and 22 do not engage and therefore the screw 4 remains stationary while the screw 34 and its piston 36 as will later appear is rotated to move downwardly.

Connected to one side of the tank 1 near the bottom thereof is the cylindrical member 25, which constitutes the dispensing member of the present apparatus. There is provided in one wall thereof, an inlet port 26, which is placed in registration with the outlet port 27 of the tank 1 so that the lubricant within the tank 1 may be fed within the dispensing member through the ports 27 and 26, there being disposed to aline the member 25, an oscillatory shell 30, which is provided with the port 30' disposed to be placed into and out of registration with the respective ports 27 and 26 and 28.

The upper end of the shell 30 is connected by means of the screw 31 to the disk 32. This disk 32 is provided with the threaded opening for the reception of the feed screw 34, whose lower end is connected by means of the yoke 35 to the piston 36. Thus the disk 32 and the shell 30 are connected for movement together and in order to impart movement to the piston 36 as the feed screw 34 is rotated, such disk 32 must be maintained in a stationary position. This is accomplished by means of the spring actuated pawl 38 adapted to seat within the recess 37 formed in the under side of the cover 36' of the member 25, such locking member 37 being so disposed as to project slightly within the periphery of the opening 39 of the cover 36' so as to be engaged by the disk 40 carried at the upper end of the feed screw 34 in its downward movement. Thus when the plunger 36 is moved to its farthest movement, the disk 40 will engage the locking member 38 and release the same from the recess 37 so that the disk 32 and the shell 30 will be rotated with the feed screw 34 so as to cause the pin 42 to ride in the arcuate slot 41 formed in the cover 36' and finally to engage the spring clip 43 which holds and receives the pin 42 in

such position. At this time, the port 30' has been moved from registration with the port 28 to registration with the ports 27 and 26 and the plunger 36 is in its lowermost position, having expelled the lubricant 70 within the shell 30 through the ports 30', 28 and through the dispensing pipe 29 to any desired place.

There is connected to the upper end of the feed screw 34, a sleeve 43, which is further 75 provided with the rectangular bore 44 for the sliding reception of the rectangular stem 45 of the shaft 46, said shaft 46 being journaled in the support 14' and carrying the gear 47 which is in mesh at all times with the gear 48 fixed upon the shaft 20. Thus it will be seen that when the crank 24 is moved in either direction, the gear 48 will transmit motion to the gear 47 and consequently rotate the shaft 46, the tubular 85 member 43 and the feed screw 34.

When it is desired to fill the tank 1 with the lubricant, the thumb screw 16 is operated to release the hinging member 15 so that the shaft section 17 carrying the gear 18 may be swung upwardly and away from the upper end of the tank 1 and out of engagement with the gear 13. The cover 10 is then rotated to release the arm 11 from the hook 12, at which time, the cover may be removed. The feed screw 4 is now removed carrying with it the plunger 6. The plunger 6 is then removed from the feed screw and the feed screw replaced with its lower end within the socket 3, at which time the lubricant may be placed within the tank 1. After the tank has been filled with the lubricant, the plunger 6 is placed upon the feed screw 4 and the cover 10 is placed in position in the upper end, the arm 11 being rotated to engage the hook 12. The shaft section 17 is now lowered so that the gear 18 is placed in mesh with the gear 13 and the hinge member 15 is locked downwardly by means of the thumb screw 16. Thus the parts are 110 now in position for operation.

Assuming that the plunger 6 is at the top and therefore the plunger 36 is at the bottom of the shell 30, the ports 27, 26 and 30' being in registration, the handle 22 is operated counter clockwise and thus imparts rotation through the gears 18 and 13 to the feed screw 4 and consequently moves the disk 6 downwardly to compress the lubricant within the tank and force that at the 11 bottom through the ports 27, 26 and 30' into the lower end of the shell 30. Simultaneously with this action, the gears 48 and 47 rotate the feed screw 34 so as to elevate the plunger 36. The threads upon the feed 1 screws 4 and 34 are so regulated that the disk 6 moves longitudinally within the tank 1 a sufficient distance only to cause a sufficient quantity of lubricant to be ejected into the shell 30 to fill the same, while the plun-

- ger 36 is moved from the extreme lower end of the shell to the upper end thereof. As the plunger 36 approaches the disk 32, the pin 42 having been seated within the spring 5 clip 43, and therefore held against rotation, the frictional rotation of the plunger 36 at the under side of the disk 32 and the continued rotation of the screw 34 will cause the disk 32 to be rotated in the opposite 10 direction or until the pin 42 assumes the position as shown in Fig. 4, at which time the spring actuated lock 38 will snap in the recess 37 and thus lock the disk 32 and the shell 30 in such position. The shell during 15 this rotation is moved to cause the port 30' to be placed from registration with the ports 27 and 26 into registration with the port 28 so that communication is shut off from the tank 1.
- 20 When it is desired to dispense the lubricant from the member 25 through the pipe 29, the crank 24 is operated clockwise at which time, the clutch members 21 and 22 remain inoperative and therefore the screw 25 4 is not operated. The shaft 46 then operates the screw 34 to cause the plunger 36 to be moved downwardly. Thus as the plunger 36 is moved downwardly, the lubricant is ejected through the ports 30' and 28 into 30 the pipe 29. As the plunger 36 approaches the lower end of the member 25, the disk 40 is brought within the recess 39 of the cover 36 and engages the spring actuated lock 38 to release the same from its recess 37 so that 35 the continued rotation of the screw 34 will produce sufficient friction upon the threaded portion 33 of the disk 32 to rotate such disk so that the pin 42 is moved from the position as shown in Fig. 4 to engage the spring clip 43, or at the extreme end of the arcuate slot 44. At that time, the shell 30 is rotated so as to place the port 30' out of registration with the port 28 and into registration with the ports 27 and 26.
- 45 What is claimed is:
1. A dispenser, embodying a main holder, a dispensing holder in communication therewith, means for ejecting the contents of the main holder into the dispensing holder, 50 means for ejecting the contents of the dispensing holder therefrom, and an operating mechanism connected to both of said means and arranged, when operated in one direction to actuate the first mentioned means to force the material from the main holder into the dispensing holder, and to retract the second mentioned means, and when operated in the other direction, to leave the first 55 mentioned means stationary while the second mentioned means is operated to force the material from the dispensing holder.
  2. A dispenser, including a main holder, a dispensing holder in communication therewith, there being a port between said holders, the dispensing holder having an outlet port, a rotatable shell within the dispensing holder having a port adapted to be brought into and out of registration with the afore- 60
- port, means for ejecting the material from the main holder into the dispensing holder, means for ejecting the material from the dispensing holder through the second mentioned port, an operating mechanism connected to said means and arranged, when operated in one direction to move the first mentioned means to eject the material from the main holder into the dispensing holder and to retract the second mentioned means, 70 and when moved in the other direction to leave the first mentioned means stationary and to actuate the second mentioned means to eject the material from the dispensing holder, and a valve device operatively connected to said mechanism and operable to close the second mentioned port when said mechanism is operated in the first mentioned direction and to close the first mentioned port when said mechanism is operated in the 75 second mentioned direction.
3. A dispenser, including a main holder, a dispensing holder in communication therewith and having an outlet, a plunger within the main holder, a screw for actuating said plunger, a plunger in the dispensing holder, a screw connected to the second mentioned plunger, and an actuating mechanism operatively connected to said screws and arranged, when operated in one direction to 80 actuate both of the screws for advancing the first mentioned plunger and retracting the second mentioned plunger, and when operated in the other direction to leave the first mentioned screw idle while the second mentioned screw is operated to advance the 85 second mentioned plunger.
4. A dispenser, including a main holder, a dispensing holder in communication therewith and having an outlet, a plunger within the main holder, a screw for actuating said plunger, a plunger in the dispensing holder, a screw connected to the second mentioned plunger, an actuating mechanism operatively connected to said screws and arranged, when operated in one direction to 90 actuate both screws for advancing the first mentioned plunger and retracting the second mentioned plunger, and when operated in the other direction to leave the first mentioned screw idle while the second mentioned screw is operated to advance the 95 second mentioned plunger.
5. A dispenser, including a main holder, a dispensing holder in communication therewith, there being a port between said holders, the dispensing holder having an outlet port, a rotatable shell within the dispensing holder having a port adapted to be brought into and out of registration with the afore- 100
- 105
- 110
- 115
- 120
- 125
- 130

said ports, a plunger within the main holder, a screw for operating said plunger, a plunger slideable within said shell, a screw connected to the second mentioned plunger, a 5 threaded member through which the screw extends and connected to said shell, means for limiting the rotary movement of the shell, and an operating mechanism connected to said screws and arranged, when operated 10 in one direction to advance the first mentioned plunger and retract the second mentioned plunger, and when operated in the other direction to leave the first mentioned plunger stationary, while the second mentioned plunger is advanced, said shell being 15 operated by the engagement of said threaded member with the second mentioned screw to open the first mentioned port when the second mentioned plunger is retracted and 20 to open the second mentioned port when the second mentioned plunger is advanced.

6. A dispenser, including a main holder, a dispensing holder in communication therewith and having an outlet, a plunger in the 25 main holder, a plunger in the dispensing holder, and an actuating mechanism embodying a driving shaft continuously connected with the second mentioned plunger to advance and retract it when said shaft is 30 operated in opposite directions, and an operative connection between said shaft and first mentioned plunger whereby when said shaft is rotated to retract the second mentioned 35 plunger, the first mentioned plunger is advanced, and when the shaft is rotated to advance the second mentioned plunger, the first mentioned plunger is disconnected from said shaft.

7. A dispenser, including a main holder, a dispensing holder in communication therewith, there being a port between said holders, the dispensing holder having an outlet port, a plunger within the main holder, a plunger within the dispensing holder, a screw for advancing the first mentioned plunger, a 45 screw connected to the second mentioned holder, a shell rotatable within the dispensing holder within which the second mentioned plunger is movable, said sleeve having a port adapted to be brought into 50 communication with the aforesaid ports, a threaded member attached to said shell and engaging the second mentioned screw whereby when the second mentioned screw is operated to advance the second mentioned 55 plunger, the shell is rotated to bring its port into register with the second mentioned port, and when the screw is operated to retract the second mentioned plunger, the port of the shell is brought into communication with 60 the first mentioned port, an operating shaft, an operative connection between said shaft and second mentioned screw, and an operative connection between said shaft and first mentioned screw and embodying a clutch 65 for disconnecting the first mentioned screw and shaft when said shaft is rotated to advance the second mentioned plunger.

In testimony that I claim the foregoing 70 as my own, I have hereto affixed my signature in the presence of two witnesses.

JAMES E. FERGUSON.
